UNITED STATES PATENT OFFICE

150,819

DESIGN FOR A DIAL TELEPHONE LOCK

Bernard Zion, New York, N. Y.

Application June 7, 1947, Serial No. 139,505

Term of patent 14 years

(Cl. D50—7)

To all whom it may concern:

Be it known that Bernard Zion, a citizen of the United States and resident of the Borough of Manhattan, city of New York, county of New York, and State of New York, has invented a new, original, and ornamental Design for a Dial Telephone Lock, of which the following is a specification, reference being had to the accompanying drawing, forming part thereof, in which Figs. 1, 2, 3, and 4 are side elevational, rear end, front end, and top views, respectively of a dial telephone lock, showing my new design in locked position, and Fig. 5 is a side elevational view like Fig. 1, but showing the same in unlocked position.

I claim:

The ornamental design for a dial telephone lock, as shown,

BERNARD ZION.
